UNITED STATES PATENT OFFICE.

HENRY C. MILLER, OF WATERFORD, NEW YORK.

STOP-MOTION DEVICE.

1,184,555.

Specification of Letters Patent. Patented May 23, 1916.

Application filed August 17, 1911. Serial No. 644,691.

To all whom it may concern:

Be it known that I, HENRY C. MILLER, a citizen of the United States, residing at Waterford, in the county of Saratoga and State of New York, have invented certain new and useful Improvements in Stop-Motion Devices; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The invention relates to improvements in stop motion devices.

The improvement is designed primarily to be used in connection with sewing machines, but is not necessarily limited to this 20 particular class of machinery.

The prime object of the invention is to provide mechanism which will effectively stop a machine at a predetermined point without jarring the parts irrespective of the 25 speed, and to provide a construction which will be easy to start the mechanism to which the invention is applied.

Another object of the invention is to provide means in a stop motion device to prevent the parts binding, in case the mechanism is set, and in case unusual power should be relieved from the mechanism. Under these circumstances I provide means whereby a locking lug will be permitted to be 35 forced over a coöoperating cam and allow the mechanism to make another revolution thereby avoiding undue strain and possible breaking of the parts.

The invention also relates to the details of 40 construction and arrangement of parts which will be hereinafter described and particularly pointed out in the claims.

In the drawings: Figure 1 is a side elevation showing the application of my improved stop motion device applied to a sewing machine. Fig. 2 is an end elevation of the same. Fig. 3 is a detail perspective view of the stop motion device, the parts being separated to better illustrate the details of 45 construction. Fig. 4 is a section on the line 4—4, of Fig. 1, looking in the direction of the arrows. Fig. 5 is a detail section, simi-

lar to Fig. 6, but showing the stopping lug in position against the cam to finally stop the mechanism. Fig. 6 is a similar view, 55 but illustrating the locking lug as riding over the cam when strain is relieved from the power or undue speed occurs.

In the drawings, the numeral 1, represents a sewing machine of conventional 60 type, including a loose pulley 2, fast pulley 3, and a trip 4, designed to automatically release the stop motion device at the end of a cycle of operation to stop the sewing mechanism.

Secured to the bed plate of the sewing machine 1, is a base 5, which forms a support for the stop motion device about to be described. Pivotally connected to the base 5, at 6, is an upwardly extending lever 7, provided with a rearwardly extended arm 8, formed with a perforation 9. On the inner face of the lever 7, is a groove or seat 10, which receives an oscillating arm 11, pivoted at 12, to said lever 7, and provided at its upper end with a projection 13. The oscillating arm is formed with a transverse guide slot 14, for a purpose to be described.

Pivotally mounted on the outer face of the 80 lever 7, at 15, is an arm 16, provided at its upper end with a concave surface 17, covered by a lining of leather, or like material 18, and designed to correspond to the contour of a hollow disk 23 secured on the shaft of the sewing 85 machine, adjacent the fast and loose pulleys and constituting a brake. Pivoted at 19, to the arm 16, is the inturned end of a rod 20, which passes through the opening 9, in the extension 8, and is provided at its outer 90 end with a thumb nut 21, between which and the end of the arm 8, is a coil spring 22. This spring acts as a cushion when the stop motion is in operation, so that when the lining 18 of the brake is clamped hard 95 against the periphery of the disk 23, the lever 7, may have a further slight continued movement.

A coil spring 25, is attached to the arm 16, and to a standard 26, projecting from 100 the base 5. This spring serves to draw the lining 18, away from the periphery of the disk 23, when the sewing machine is in operation, sufficiently to obviate friction. The

movement of the arm 16, under the influence of the spring 22, is limited by a stop pin 28, in said arm, the inner end of said stop pin abutting against one edge of the lever 7, as clearly shown in Fig. 4.

Pivoted to the base 5, is a tilting frame 30, provided with an arm 31, to which is attached a chain or other operating connection, whereby to shift the belt from the loose 10 to the fast pulley, as will be described. Extending upwardly from the frame 30, are two arms 32, and 33, the latter being formed with a socket to receive a stem 34, of a belt shifter 35. Connecting the two arms 32 and 15 33, is a guide bar 36, which passes through the slot 14, in the oscillating arm 11, whereby a guide is formed for said oscillating arm in the movement of the parts.

In the hollow portion of the disk 23, and 20 revolving with the latter is a cam 38, having a substantially concentric portion 39, and a substantially inclined portion 40, and a short concentric portion 41, which merges into an inclined cam surface or abutment 25 42. The abutment is the element with which the projection 13, coöperates to bring the sewing machine mechanism to a final stop, and at a predetermined point at the proper time, but is so constructed that if 30 the stop motion has not been properly adjusted, the projection may ride over the abutment to prevent the breaking and binding of the parts as indicated in Fig. 6.

In operation, assume that the belt 45, is 35 running on the loose pulley 2, and it be desired to operate the machine. The operator pulls the chain so as to tilt the frame 30, on its pivot, which movement also draws the belt shifter 35, laterally and with it the belt 40 45, from the loose pulley to the fast pulley 3, as shown in Fig. 1. When the frame 30, is tilted the guide bar 36, engaging the oscillating bar 11, rocks the latter on its pivot 12, and thereby removes the projection 13, 45 from the path of movement of the cam 38. When this occurs the brake 16, is drawn from the periphery of the disk 23 by the spring 25 and is held in this position by the stop pin 28. It may also be stated that the 50 oscillating bar 11, is confined in the seat 10, so that when lever 7 is rocked it will also rock the bar 11. When the stop motion is thrown as described, the belt 45 engages the fast pulley and operates the sewing machine 55 in the usual manner, and when the cycle of operation is complete the trip 4, is automatically disengaged from the arm 31 and a spring 50, tilts the frame 30, and the belt 45, is shifted again to the loose pulley. In 60 this movement the oscillating bar 11, is also returned to its normal position in the seat 10, and the projection 13, is brought into the path of movement of the operative surface of the cam 38. The projection does not contact with the surface 39, but upon reaching

the inclined surface 40 the oscillating lever 11 is rocked, and as said lever fits snugly in the seat 10, it follows that the lever 7, will also be rocked on its pivot 6, against the tension of the spring 22, which exerts a pull 70 on the arm 16, and applies the brake. By the time the projection 13 reaches the highest point of the inclined surface 40 of the cam 38, assuming the spring 22, has been placed under proper tension, the speed 75 of the machine will be substantially under control, and what may be termed a preliminary stopping of the mechanism takes place. The substantially concentric portion 41, of the cam 38, serves as a means to reduce the speed after the preliminary braking of the mechanism has occurred, through the action of the cam surface 40, and by the time the projection reaches the lug or abutment 42, the speed has been so reduced that 80 little or no jar occurs and the mechanism is brought to an absolute stop and at a predetermined point. When the arm 11, is rocked by the cam, the arm 8, is forced against the spring 22, and the latter against the nut 21. 90 Hence the brake is drawn tight against the disk 23.

If, for any reason the spring 22, has not been properly adjusted, so as to create friction enough between the brake and the disk 95 23 to effectually stop the sewing or other mechanism at the time the projection 13, encounters the abutment 42, the said projection will ride over the abutment as shown in Fig. 6, and the fast pulley will make another 100 revolution and the mechanism will be stopped by the projection 13, again engaging the cam and contacting with the abutment 42. Under these circumstances the operator must see to it that the thumb nut 21, 105 is adjusted to place the spring 22, under proper tension so as to effectually apply the brake on the disk 23, under the influence of the projection and cam, that the mechanism be stopped at the desired point. If the tension of the spring be too great, and the projection 13, does not reach the abutment when the mechanism is stopped, the spring must be adjusted accordingly so that in 110 every instance the projection must come into 115 contact with the final abutment or braking surface to insure that the mechanism upon the completion of each cycle of movement stops at a predetermined point.

From the foregoing description, it will be 120 seen that by the arrangement of the parts described a positive and effective stop motion device is provided, and one which by reason of the minute adjustment will insure the stopping of the mechanism at any 125 predetermined point and one which cannot jar and break the parts.

What I claim is:

1. In a stop motion device, the combination of fast and loose pulleys, a tilting 130

frame having a belt shifter, an arm pivoted to swing at right angles to the swinging frame and formed with a seat, an element pivoted to the arm and movable with the 5 tilting frame, said element having a projection, a cam revolving with the fast pulley and with which the projection engages, a brake arm coöperating with the fast pulley, and a resilient connection between the 10 brake arm and the pivoted arm.

2. In a stop motion device the combination of fast and loose pulleys, a tilting frame having a belt shifter, an arm pivoted to swing at right angles to the tilting frame, 15 a brake coöperating with the fast pulley, a cam having a projection and revolving with the fast pulley, a resilient connection between the pivoted arm and the brake, and means pivoted to the pivoted arm and movable laterally with the tilting frame to cause 20 the projection on the cam to apply the brake to the fast pulley.

3. In a stop motion device, the combination of fast and loose pulleys, a tilting 25 frame, an arm pivoted to swing at right angles to the tilting frame, an oscillating lever pivoted to the arm and movable with the latter and the tilting frame, a brake pivoted to the arm, a resilient connection 30 between the brake and the arm, a cam revolving with the fast pulley and coöperating with the oscillating lever to rock the pivoted arm and apply the brake when the 35 swinging frame is moved toward said fast pulley.

4. In a stop motion device, the combination of fast and loose pulleys, a swinging 40 frame having a belt shifter, an arm pivoted to swing at right angles to the swinging frame, said arm having a seat and a perforated extension, an oscillating lever pivoted in the seat and provided with a 45 guide to engage the swinging frame, a projection on the oscillating lever, a pivoted brake, a cam revolving with the fast pulley, a rod connected to the brake and extending through the perforation in the extension, a spring on the rod and bearing against 50 the extension, whereby when the swinging frame is moved toward the loose pulley, the cam will operate on the projection and apply the brake to said pulley.

5. In a stop motion device, the combination of fast and loose pulleys, a cam revolving 55 with the fast pulley, said cam having a projection, a pivoted arm, an oscillating lever pivoted to the arm and having a projection which coöperates with the cam, 60 means for tilting the oscillating lever toward and from the cam, a brake coöperating with the fast pulley, a resilient connection between the brake and the pivoted arm, means for holding the brake away 65 from the fast pulley when the former is

in normal position, the cam being arranged to pass the oscillating lever if the resilient connection is loose.

6. In a stop motion device, the combination of fast and loose pulleys, a cam revolving with the fast pulley, a brake coöperating with the fast pulley, a pivoted arm formed with a seat and having an extension, a rod supported by the extension and pivoted to the brake, an adjusting nut on 70 the rod, a spring between the adjusting nut and the extension, an oscillating lever mounted in the seat and pivoted to the arm, said oscillating lever having a guide and a projection, the latter coöperating with the cam, a tilting frame having a guide bar with which the guide on the oscillating lever engages to cause the said lever to move with the tilting frame, a belt shifter supported by the tilting frame to shift a belt from the 75 fast to the loose pulley and vice versa.

7. In a stop motion device, the combination of fast and loose pulleys, a tilting frame, a belt shifter supported on the tilting frame, an arm pivoted to swing at right angles to the tilting frame, an oscillating lever pivoted to the pivoted arm and movable with the tilting frame, a brake pivoted to the pivoted arm, and a resilient connection 90 between the brake and the pivoted arm, whereby when the oscillating lever is rocked by the tilting frame into the path 95 of the cam the brake will be applied to the fast pulley.

8. In a stop motion device, the combination of an element having a braking surface, a pivoted arm, a lever pivoted to the pivoted arm, a brake pivoted to the pivoted arm and coöperating with the braking 100 surface, a resilient connection between the brake and the pivoted arm, and means for oscillating the lever to set same in braking position, and means coöperating with the lever to rock the pivoted arm to operate the 105 brake.

9. In a stop motion device, the combination of an element having a braking surface a cam provided with an inclined surface and a projection, an oscillating lever 115 coöperating with the cam, a pivoted arm to which the oscillating lever is pivoted, a brake pivoted to the pivoted arm, a connection including a spring, between the brake and the pivoted arm, and means for oscillating the oscillating lever toward the cam whereby the inclined surface thereof will gradually apply the brake on the braking surface and the projection will apply a final pressure of the brake on the braking surface 120 to stop a machine at a predetermined point.

10. In a stop motion device, the combination of fast and loose pulleys, a tilting frame having a guide bar, a belt shifter supported on the tilting frame, an arm pivoted at right 125

angles to the tilting frame and formed with a seat, an oscillating lever mounted in the seat and pivoted to the arm, said oscillating lever having a guide to coöperate with the 5 guide bar, a lug extending from the oscillating lever, a brake pivoted to the arm, a rod connected to the brake and supported by the arm, a spring on said rod, means for adjusting the tension of the spring, an adjustable stop for limiting the movement of the 10 brake, and a spring for holding the brake away from the fast pulley when the parts are in normal position.

11. In a stop motion device, the combination 15 of a cam, a frame, tilting toward and from the cam, a pivoted arm, an oscillating lever pivoted in the arm to oscillate in the direction of the tilting frame, a lug on the oscillating lever to coöperate with the 20 cam and a spring resisting the impact of the lug with the cam.

12. In a stop motion device, the combination 25 of a movable frame, an arm pivoted to move at an angle to the movable frame, a movable lever mounted in the pivoted arm, a lug on the latter movable lever, a brake lever, movably mounted on the pivoted arm, a cushion, interposed between said brake lever and the pivoted arm, and a cam with 30 which the lug coöperates, to operate the pivoted arm and apply the brake and lever.

13. In a stop motor device, the combination 35 of a shaft, a cam on the shaft, said cam having a lug, a pivoted lever, an oscillating lever pivoted to the pivoted lever to oscillate at right angles to the movement of said pivoted lever, a projection on the oscillating lever to coöperate with the cam and lug thereon, a brake lever, a cushion between 40 the brake lever and the pivoted lever, and means for moving the oscillating lever to bring the projection into the path of the cam, whereby said oscillating lever and said pivoted lever will be rocked and by means 45 of the cushion, operate the brake lever.

14. In a stop motion device, the combination 50 of a disk, a cam, a brake lever coöperating with the disk, a tilting frame and means between the tilting frame and the brake lever for operating the latter, including two levers, pivoted at right angles to each other and a cushion between said pivoted levers and the brake lever, one of said pivoted levers being operated by the cam 55 to operate the brake lever on the disk.

15. In a stop motion device, the combination 60 of a disk, fast and loose pulleys, a cam, a tilting frame, a belt shifter carrier by the tilting frame, a pivoted lever, provided with a member having a projection to coöperate with the cam, a pivoted brake lever, a yielding connection between the pivoted brake lever and the pivoted lever, whereby when the tilted frame is operated the projection 65 will be brought into the path of the cam and

a belt will be shifted and the brake lever will be applied to the disk.

16. In a stop motion device, the combination 70 of an element having a braking surface, a brake coöperating with the braking surface, means including a pivoted setting lever to move the brake into contact with the braking surface, a cushion spring connected with the brake and with which the brake operating means coöperate when applying the brake, a cam for operating on the setting lever, and means for positioning the setting lever in the path of movement of the cam.

17. In a stop motion device, the combination 75 of an element having a braking surface, a brake coöperating with the braking surface, means including a setting lever pivoted to swing at right angles to the movement of the brake to move said brake into contact with the braking surface, a spring connected with the brake and with which the brake operating means coöperate when applying the brake, a cam for operating on the setting lever, and means for rocking the setting lever at right angles to the movement of the brake to position said lever in the path of movement of the cam.

18. In a stop motion device, the combination 80 of an element having a braking surface, a brake coöperating with the braking surface, a pivoted supporting arm to which the brake is pivoted, a resilient connection between the brake and the supporting arm, a setting lever pivoted to the supporting arm, a cam, and means for rocking the setting lever to position same in the path of the cam to apply the brake to the braking surface.

19. In a stop motion device, the combination 85 of an element having a braking surface, a brake coöperating therewith, a setting lever, a pivoted arm, said arm forming a support for the brake and the setting lever, a spring interposed between the pivoted arm and the brake, a device for operating on the setting arm at predetermined times, and means for positioning the setting lever in the path of the said operating device whereby the latter may cause the brake to engage 90 the braking surface.

20. In a stop motion device, the combination 95 of an element having a braking surface, a brake, a supporting arm, a setting lever, a yielding connection between the brake and the setting lever, said arm, setting lever and brake moving together when the brake is in operation, and means for acting on the setting lever to apply the brake on the braking surface at predetermined times.

21. In a stop motion device, the combination 100 of an element having a braking surface, a brake, a pivoted supporting arm, a connection between the supporting arm and the brake including a spring with which the 105

arm abuts and which is placed under tension when applying the brake to the braking surface, a setting lever carried by the arm and movable toward and away from the same, a cam, and means for moving the setting lever in position to be engaged by the cam to operate the brake.

In testimony whereof I have signed my name to this specification in the presence of two subscribing witnesses.

HENRY C. MILLER.
